UNITED STATES PATENT OFFICE.

JOHN B. THIES, OF DAYTON, OHIO.

AUTOGRAPHIC REGISTERING APPARATUS.

SPECIFICATION forming part of Letters Patent No. 410,616, dated September 10, 1889.

Application filed April 13, 1889. Serial No. 307,164. (No model.)

To all whom it may concern:

Be it known that I, JOHN B. THIES, a citizen of the United States, residing at Dayton, in the county of Montgomery and State of Ohio, 5 have invented certain new and useful Improvements in Autographic Registering Apparatus; and I do hereby declare that the following is a full, clear, and exact description of the invention, which will enable others skilled 10 in the art to which it appertains to make and use the same, reference being had to the accompanying drawings, and to the letters of reference marked thereon, which form a part of this specification.

15 My invention relates to improvements in autographic registering apparatus, the several features of which will be fully hereinafter set forth.

The object is to preserve detachable copies 20 of any instrument of writing sought to be preserved, and the accomplishment of this object is effected by the mechanism illustrated in the accompanying drawings, comprising two sheets, in which—

25 Figure 1 is a fragmentary side elevation of the apparatus. Fig. 2 is a top view of the same with a part of the top cut away and other parts omitted. Fig. 3 is a transverse section on line *x*, Fig. 1. Fig. 4 is a transverse section of the tablet-frame on line *y*, Fig. 5. Fig. 5 is a top view of the tablet-frame with the transfer-paper attached.

30 Like letters designate like parts throughout the several views.

35 A is the frame. The rear part to the left of the center is closed by a lid, which may be attached by hinges or be held in grooves of the said frame, and when desirable may be secured by a lock. On the front end is held 40 the tablet-frame K in an inclined position. Spools 1 and 2 are supported in bearings in the sides of the frame, and on said spools are respectively strips of paper 3 and 4.

45 At Fig. 5 the tablet-frame K is shown as being supported in notches of the frame. This tablet-frame consists of a plane upper surface rounded at the ends, projections to engage the frame, and flanges at the ends to support the two rollers *m m*, on which are 50 rolled the ends of the transfer-paper N, Figs. 4 and 5.

M M are bearings for the gripping-rollers I and J, and are attached to the sides of the frame. The upper parts are hollow, for the purpose of receiving spiral springs *s*, which 55 press the lower roller against the upper. One of these bearings is shown in section at M, Fig. 3. The roller I has a hard surface of wood or metal, and the roller J is covered with rubber, and to the shaft of the latter is 60 attached the hand-wheel U, for the purpose of rotating the rollers.

The paper strip 4 passes beneath the roll or strip 3, and thereby produces sufficient friction to keep both strip stout. The former strip, from the roll of the latter, passes over the transfer-paper between the gripping-rollers and through an orifice in the housing over said rollers; but in passing from the rollers to the said orifice it passes beneath the edge of 70 the blade 5 of the shears. The strip 3 passes up and beneath the transfer-paper between the rolls, and is separated from the top strip by the rod *r*, and likewise passes under the edge of the fixed blade of the shears, and 75 both ends are separated by the operation of the shears.

On the frame over the tablet-frame is attached the open plate or window O, and within this space the writing is done, as indicated at Fig. 2.

The blade 5 of the shears is fixedly attached to the side of the frame and extends across the top of the same. To this blade is riveted, as usual, the blade 6, whose end is pivotally 85 connected to the crank F on the shaft G, and by this means the requisite movement is given to operate the shears. This shaft has bearings in the sides of the frame. Central on the shaft is the arm E, and external to the frame 90 is attached the operating-lever H. The relation of these parts is best shown at Fig. 3.

On cleats attached to the sides of the frame is placed the block B, and over this block, in a groove on its face, is the bolt 8, which passes 95 through the sides of the frame, and thereby holds said block against the upward pressure of the springs D, attached to the under side of the same. The free ends of this pair of springs rest on the transverse part of the angular filing-pin C. This filing-pin has points 100 bent at a right angle to the shaft and is held

in orifices of the thimbles *w*, held in the block B. When the handle II is drawn forward, the filing-pin penetrates the paper slip 3, entering the holes *z z* of the top, and at the same instant the shears sever both slips of paper. When the handle is carried back, the filing-pin drops down, carrying with it the perforated slip. When a large number of slips have accumulated in the box, the bolt 8 is withdrawn and the block B raised out of the frame or case and the slips removed for a proper filing. When the two strips of paper are placed as heretofore described, the turning of the hand-wheel U carries the two sheets forward, and they are disposed of as described. The writing being done on the external sheet, the transfer-paper gives a fac-simile impression on the inner sheet.

From the prior description the operation is sufficiently apparent, and it is only necessary to add that the transfer-paper is changed in position on the tablet-frame as it becomes necessary to secure distinctness of impression by the rollers *m m* of the tablet-frame.

Having fully described my invention, what I claim, and desire to secure by Letters Patent, is—

1. In an autographic registering apparatus, the combination of the frame A, the spools 1 and 2, so arranged that the strip 4 of the former is drawn beneath the roll 3 to give tension to both of said strips by moving the same in contact in opposite directions, the tablet-frame K, with its transfer-paper, and feeding-rollers I J, with handle to operate the latter, substantially as shown and described.

2. In an autographic registering apparatus, the combination of the frame, the rollers 1 and 2, with the arrangement of the strips of paper as being withdrawn therefrom, the tablet-frame K, to support said strips with the intermediate transfer-paper, the carrying-rollers I and J, the shears of parts 5 and 6, connecting-rod 7, crank F, shaft G, and operating-lever II, substantially as described.

3. In an autographic registering apparatus, the combination of the frame, the detachable filing-block B, with thimble-guides *w w*, the angular filing-pin C, held loosely in said guides, the depressing-spring D, attached to said block 50 and bearing downwardly against the transverse part of said pin, arm E, shaft G, and operating-arm H, substantially as described.

4. In an autographic registering apparatus, the combination of the frame A, shaft G, arm E, filing-pin C, carried upwardly by said arm to pierce the under strip of paper as it is thrust against the top of said frame and pierced by the filing-pin points entering orifices *z z* of said top, the crank F, connection-rod 7, the 60 moving blade 6 and fixed blade 5, and the operating-handle H, these parts to simultaneously sever the two strips of paper and fix the under strip on the said filing-pin, substantially as described. 65

5. In an autographic registering apparatus, the combination of the frame A, the shaft G, with the operating-handle H attached, crank F, connection-rod 7, and shears of parts 5 and 6, to sever the strips of paper carried forward 70 by the feeding-rollers, substantially as described.

6. In an autographic registering apparatus, the frame having the top with orifices *z z*, in combination with the filing-block B, with 75 guides *w w*, held down against cleats in said frame, the bolt 8, to hold the same down against the depressing-springs D D, the arm E, shaft G, with operating-arm H attached, and filing-pin C to pierce the under strip 3, substantially as described.

In testimony that I claim the foregoing as my own I affix my signature in presence of two witnesses.

JOHN B. THIES.

Witnesses:

B. PICKERING,
SUMNER T. SMITH.
